UNITED STATES PATENT OFFICE.

OTTO W. SCHAUM, OF PHILADELPHIA, PENNSYLVANIA.

DESIGN FOR A VIBRATOR-LEVER FOR SHEDDING MECHANISMS.

SPECIFICATION forming part of Design No. 33,830, dated January 1, 1901.

Application filed December 6, 1900. Serial No. 33,962. Term of patent 14 years.

To all whom it may concern:

Be it known that I, OTTO W. SCHAUM, a citizen of the United States, residing in Philadelphia, in the county of Philadelphia and State of Pennsylvania, have invented a new and useful Design for a Vibrator-Lever for a Sheding Mechanism; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In the accompanying drawings, wherein corresponding letters of reference indicate like parts, I have fully illustrated my invention.

In said drawings, Figure 1 is a top plan view of a vibrator-lever for a shedding mechanism constructed in accordance with my invention. Fig. 2 is a view in side elevation of said vibrator-lever. Fig. 3 is a view on the line *x x* in Fig. 1, and Fig. 4 is a view on the line *y y* in Fig. 1.

As essential features of design the vibrator-lever which is the subject of the said design comprehends in its construction two concavities in its under side, which are separated by a projection of said vibrator-lever. The shank portion *a* of the lever consists of a plain flat bar which is somewhat thickened,

as at *b*, in its rear portion. At its rear or free end said shank portion terminates in a hook *c*, produced by forming a deep recess *d* in the under edge of said shank portion. This hook is divided into two substantially similar members by bifurcating it, as at *e*. The other end of said shank portion merges into a curved portion *f*, from which extends a projection *g*. Each side of this projection said curved portion is formed with a concavity or incurvation *h*. In the projection *g* is formed a bearing-orifice *i*, while at the juncture of the shank portion and curved portion of the lever and on the upper edge of the latter is a recessed enlargement *k*. The said incurvations or concavities *h* and the bearing-orifice *i* are respectively bordered by reinforcements or flanges *l m*.

Having thus fully described my invention, what I claim as new, and desire to secure by Letters Patent, is—

The design for a vibrator-lever for a shedding mechanism substantially as herein shown and described.

In testimony that I claim the foregoing I have hereunto set my hand this 22d day of November, 1900.

OTTO W. SCHAUM.
